(57) **CLAIM**

The ornamental design for a oval container lid, as shown and described.

DESCRIPTION

FIG. 1 is a perspective view of the oval container lid in an open position;

FIG. 2 is a bottom view of the inventive lid depicted in FIG. 1;

FIG. 3 is a front view of the inventive lid depicted in FIG. 1 in a closed position;

FIG. 4 is a right side view of the inventive lid depicted in FIG. 3; and,

FIG. 5 is a right side view of the inventive lid depicted in FIG. 1.

The broken lines in the drawings are for illustrative purposes only and form no part of the claimed design.
